UNITED STATES PATENT OFFICE.

WILLIAM PAINTER, OF BALTIMORE, MARYLAND, ASSIGNOR TO THE CROWN CORK AND SEAL COMPANY, OF SAME PLACE.

BOTTLE-SEALING DEVICE.

SPECIFICATION forming part of Letters Patent No. 608,157, dated July 26, 1898.

Application filed February 9, 1893. Serial No. 461,607. (No model.)

To all whom it may concern:

Be it known that I, WILLIAM PAINTER, of the city of Baltimore, in the State of Maryland, have invented certain new and useful 5 Improvements in Bottle-Sealing Devices; and I do hereby declare that the following specification, taken in connection with the drawings furnished and forming a part of the same, is a clear, true, and complete description 10 of my invention.

My said improvements pertain to that class of bottle-sealing devices which involve the use of bottles having on their heads an annular locking-shoulder together with sealing- 15 disks which are maintained in sealing contact with the lips of the bottles by means of hard-metal sealing-caps.

My invention consists in providing flanged hard-metal caps with a series of detaching-lugs projected from the flange of each cap and remote from its edge above its point of engagement with the locking-shoulder on the bottle. The lower surfaces of said lugs afford shoulders with which any suitable bottle-opener may reliably engage for detaching the caps from bottles. These lugs are integrally formed by an outward displacement of the metal at more or less regular intervals and preferably in such close proximity to each 25 other as will enable a bottle-opener to be applied without reference to any special peripheral location on the cap and also so that several of the lugs may be simultaneously engaged by an opener. The portion of the cap-flange which is made to engage in locking contact with the bottle is sufficiently thin and ductile to enable it to be closed inwardly against the glass by the application of rolling or "spinning" pressure.

To more particularly describe my present invention, I will refer to the accompanying drawings, in which—

Figure 1, in side view, top view, and section, illustrates one of my sealing-caps in a desirable form without its sealing-disk. Fig. 2, in section, illustrates a bottle-head with one of said caps applied thereto with a sealing-disk. Fig. 3, in side view and section, illustrates one of my caps having detaching-lugs 50 differing in form from those shown in Fig. 1.

The cap A, Fig. 1, is composed of suitable

hard metal, preferably tinned sheet-iron, and its interior surface is shaped so as to conform quite closely to the exterior shape of the lip of the bottle with which it is to be used. The 55 cap-flange, near its edge *a*, is plain, and the metal is sufficiently thin and soft to enable it to be properly forced into good engaging contact with the locking-shoulder of a bottle. The several detaching-lugs *b* are located sufficiently remote from the edge *a* to not interfere with the proper working of the metal in applying the cap to a bottle and also sufficiently remote from the top of the cap to not relieve a sealing-disk from desirably uniform 60 compression; but this would be immaterial if the cap was used for confining an ordinary cork in a bottle-neck. These lugs *b* are formed by outwardly displacing the metal in the flange, so as to afford an abrupt shoulder 70 at the lower end of each lug, as at *b'*, and in this instance at said lower end there is an opening into the cap, as indicated in the sectional view of Fig. 1, the abrupt shoulder in this case being afforded by the edge of that 75 portion of the metal which is outwardly displaced at the base of each lug. The sealing-disk *c* may be varied in its character, but is preferably a thin cork disk.

The bottle-head *B*, as shown in Fig. 2, has 80 a rounded lip and an annular locking-shoulder at *d*. The cap *A*, with its disk *c*, is placed on the bottle-head and pressure applied to the top of the cap for closely conforming the disk to the lip of the bottle, and then while 85 still under sealing pressure the flange is rolled into contact with and beneath said shoulder, thus maintaining the disk in proper sealing contact with the lip of the bottle. The union of a hard-metal cap thus applied 90 to a bottle is so firm that a powerful prying action is required, as by the use of any form of bottle-opener which by engaging with such detaching-lugs will operate with leverage in wrenching the cap from the bottle, although the lugs located remotely from the edge of the flange, as described, will serve as detaching-lugs, regardless of the manner in 95 which a reliable locking union of the cap and bottle may be effected.

It is not essential that the lower ends of the detaching-lugs should be open or that

they should be otherwise precisely formed, as shown in Figs. 1 and 2, as, for instance, as shown in Fig. 3, the cap A' has pear-shaped detaching-lugs b^2 , the lower or large ends of 5 which are not open, but the metal is so bent and displaced as to afford a shoulder sufficiently abrupt to enable a suitable opener to properly engage therewith.

As compared with a cap having an annular 10 detaching-rib my present cap, having the detaching-lugs, is, when in use, somewhat less liable to vary in its compressing relations to a sealing-disk than a cap having an annular rib, because the latter is formed by fold- 15 ing or bending a portion of the flange upon itself in a line transverse to the line of displacing strain, so that when under extraordinary heavy gaseous pressure the upper and lower sides of the rib might be slightly parted, 20 so as to correspondingly relieve the disk from compression, whereas with my present caps the metal between the lugs is not folded, and

hence is incapable of yielding to any outward strains to which the cap can possibly be subjected.

Having thus described my invention, I claim as new and desire to secure by Letters Patent—

1. A metallic bottle-sealing cap, having a flange, provided with outwardly-projecting 30 lugs, located remotely from the edge of the cap, substantially as described.

2. The combination of a bottle having on its head an annular locking-shoulder, and a metallic sealing-cap containing a sealing-disk 35 under compression, and having a flange provided with outwardly-projecting detaching-lugs, and also having its edge below said lugs, in reliable locking contact with the annular locking-shoulder, substantially as described. 40
